(57) **CLAIM**

The ornamental design for an acoustic deterrent housing, as shown and described.

DESCRIPTION

FIG. 1 is a front perspective view of the acoustic deterrent housing showing my new design;

FIG. 2 is a rear perspective view thereof;

FIG. 3 is a front elevation view thereof the rear elevation view being a mirror image thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the acoustic deterrent housing that form no part of the claimed design.
